THREAD GRINDING MACHINE

Guenther Brinkmann, Detroit, Mich., assignor to
 Ex-Cell-O Corporation, Detroit, Mich., a corporation of Michigan

Application March 18, 1942, Serial No. 435,224

14 Claims. (Cl. 51—95)

The present invention relates to improvements in thread grinding machines, and has reference particularly to machines adapted for the grinding of internal threads.

One of the objects of the present invention is to provide a novel thread grinding machine having a longitudinally reciprocable work head, a transversely reciprocable grinding wheel head movable selectively in one direction into operative position or in the other direction into idle position, a dressing mechanism for dressing the grinding wheel in the idle position, and means for imparting a dresser feed to said wheel head and simultaneously adjusting the effective operative position of the wheel to compensate for the dresser feed.

Another object is to provide a new and improved internal thread grinding machine of the foregoing character having an automatic cycle in which the grinding wheel will be dressed selectively either after a predetermined number of grinding passes, or after the completion of a single workpiece, or after the completion of a predetermined number of workpieces.

A further object is to provide a novel thread grinding machine of the foregoing character having a cross feed mechanism for imparting an incremental cross feed to the grinding wheel at the end of each grinding pass, and including means selectively available for automatically retracting the grinding wheel from the work during the passes in one direction or the other of the work head reciprocation.

Other objects and advantages will become apparent as the description proceeds.

Referring to the drawings,

representing three typical operating cycles of the machine.

Fig. 26 is a diagrammatic representation of the hydraulic system of the machine.

Fig. 27 is a diagrammatic representation of the control valves and valve actuators included in the hydraulic system.

Figs. 28 and 29 are a diagrammatic representation of the electrical control system of the machine.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawings, the machine constituting the exemplary embodiment of the invention is of the type adapted for grinding internal screw threads, and comprises an elongated horizontally disposed base 1 formed on the top with a longitudinal set of ways 2 for supporting a work head 3, and having a rearward extension 4 formed with a set of transverse ways 5 for supporting a tool head 6. A rotary tool spindle 7 is mounted in the tool head 6 and supports a suitable grinding wheel G. A work spindle 8 is mounted in the work head 3, and is adapted to rotate and translate a workpiece W axially through cutting engagement with the grinding wheel G in timed relation to the rotation as determined by the lead of the thread or threads to be ground.

The tool head 6 is shiftable transversely of the work spindle 8 to locate the grinding wheel G either in operative position at the forward limit of travel or in idle or dressing position at the rearward limit of travel. When the grinding wheel G is located in the operative position, it is substantially aligned with the work spindle 8 to enter and take a grinding pass or series of passes through the workpiece W. Relative working translation between the grinding wheel G and the workpiece W is obtained by reciprocating the work spindle 8 through a selected program of movements, such for example as a rapid approach to grinding position, a slow forward feed through the working range, and a rapid return to idle position.

The spindle 8 may be rotated in either direction relative to the translation in accordance with the hand of the thread to be ground. At each reversal of translation, the rotation of the spindle 8 is reversed, and the spindle is shifted axially to compensate for backlash in the drive. The work spindle 8 also is shiftable axially for lead pickup, and is adapted to be indexed when grinding multiple threads to locate the threads successively in correct cutting relation to the grinding wheel G.

A cross feed mechanism 9 is provided for automatically adjusting the operative position of the wheel G step-by-step in timed relation to the successive working passes of the spindle 8 until the workpiece W has been ground to final size. A retract mechanism 10 is automatically operable to separate the grinding wheel G laterally from the workpiece W during all rapid traverse movements without affecting the setting of the cross feed mechanism.

Mounted in a fixed position on the base exten-

sion F at the rear of the grinding wheel G is a suitable dressing mechanism 11 for truing the grinding wheel G when the tool head 6 is shifted into offset idle position. A dresser feed mechanism 12 is automatically operable to adjust the idle position of the tool head 6 incrementally toward the dressing tools for each dressing operation, and simultaneously to adjust the operative position of the tool head relatively to the workpiece W independently of the cross feed mechanism 9 to compensate for the reduction in diameter of the grinding wheel G in the dressing operation.

The operation of the machine is controlled by an electrical system in which the movements of the main units are interlocked and timed, and which is selectively adjustable to obtain any one of a substantial number of automatic machine cycles. Thus, the electric control system may be set to effect grinding at either rapid traverse or feed rate, and during only the inward pass or only the outward pass or both inward and outward passes, in one or a series of complete working reciprocations, and the grinding wheel G may be dressed after two passes, or any multiple thereof, or before finish grinding, or at the completion of each workpiece or a plurality of workpieces, within the capacity of the counting mechanism.

The work head

The work head 3 comprises a longitudinal sub-base or slide 20 which is mounted on the ways 2 of the machine base 1 for manual adjustment longitudinally of the work spindle 8, and which, during the normal machine operation, is clamped in position of adjustment.

To provide means for effecting the manual adjustment, the outer end of the base slide 20 is formed between the ways 2 with a longitudinal bore 21 having a counterbore 22. A stationary nut 23 is fitted in the counterbore 22, and has an outer end flange 24 bolted to the slide 20. An adjusting screw 25 extends through threaded engagement with the nut 23 into the bore 21. The outer end of the screw 25 is rotatably anchored against endwise movement in an end wall 26 on the machine base 1, and has a squared end 27 for engagement by a suitable hand tool (not shown).

The base slide 20 is adapted to be secured adjacent its ends to the base 1 by two similar manually operable clamping devices. Each clamping device comprises transverse clamping bar 28 slidably engaging at opposite ends in two longitudinal grooves 29 formed in the inner sides of the ways 2. A clamping plunger 30 extends upwardly through an opening in an intermediate portion of the clamping bar 28 and has a head 31 engaging the underside thereof. The upper end of the plunger 30 extends slidably into a vertical bore 32 in the base slide 20, and is formed in one side with a conical recess 33. A clamp screw 34 is adjustably threaded through the base slide 20 into the bore 32, and has a conical pin 35 on the inner end adapted for wedge engagement with the upper side of the recess 33. The screw 34 is provided with a squared end 36 adapted to be engaged by a suitable hand tool (not shown). It will be seen that when the screw 34 is turned inwardly, the plunger 30 will be forced upwardly to clamp the bar 28 securely against the upper sides of the grooves 29 in any position of adjustment of the base slide 20.

Mounted on the top of the base slide 20 for translation longitudinally of the spindle 8 is a

work slide 37 preferably formed integral with a longitudinal spindle housing 38. The work slide 37 has two depending side flanges 39 formed with notches 40 in which longitudinal V-ways 41 are secured in spaced opposed relation. A flat guide plate 42 is secured to the top of the base slide 20 between the flanges 39, and is formed along opposite side edges with V-ways 43. Suitable roller bearings 44 are interposed between and in bearing engagement with the complementary surfaces of the ways 41 and 43 to complete the guide relationship.

Secured in opposite ends of the spindle housing 38 are two flanged bearing cups enclosing anti-friction bearings 45. The work spindle 8 extends axially through the spindle housing 38, and is suitably journaled at opposite ends in ball bearings 45. The forward end of the spindle 8 is formed with a taper socket 46 and an outer end flange 47 to mount a chuck or other suitable support (not shown) for the workpiece W. The rear end of the spindle 8 is closed by a cap 48 formed with an axial sleeve 49. Secured in the sleeve 48 and extending therefrom through the spindle 8 is a tube 50 for directing coolant to the workpiece W. Coolant is adapted to be supplied to the tube 50, through a line including a flexible hose 51 connected to the sleeve 49, from a tank 52 by a coolant pump (not shown) driven by an electric motor 53.

The spindle 8 is adapted to be driven from a reversible two-speed electric motor 56 at rapid traverse and feed rates, and in either direction in relation to the translation of the work slide 37 through a speed-change mechanism 57 to a worm shaft 58 within the base slide 20, then through a speed reduction gearing 59 to a longitudinal drive shaft 60 anchored for axial movement with the work slide, and then through a gear-change mechanism 61 selectively adjustable to control the direction of rotation in relation to the drive and to permit indexing when grinding multiple threads.

The motor 56 is mounted on one side of the base extension 2, and is connected through a V-belt 63 to a multiple groove pulley 64 forming part of the speed-change mechanism 57. In the present instance, the pulley is provided with five belt grooves 65 of different diameters so as to afford five different selective speeds for any given speed of the motor 56.

The speed-change mechanism 57 comprises a clutch housing 66 mounted on the rear of the base slide 20 and open at opposite ends. Two bearing caps 67 and 68 are secured to the ends of the housing 66, and enclose suitable antifriction bearings 69 and 70. Journaled in the bearing 69 is a stub shaft 71 integral with a plate 72 secured to one side of the pulley 64. The plate 72 and a spaced wall 73 in the pulley 64 define a chamber 74 for enclosing a planetary gear drive. Extending from the chamber 74 rotatably through the stub shaft 71 into the clutch housing 66 and supported at the inner end in the bearing 70 is a tubular shaft 75 in axial alignment with the worm shaft 58. A terminal outlet shaft 76 is journaled at one end in the wall 73 and extends rotatably through the shaft 75 into coaxial splined engagement with the worm shaft 58. The shafts 75 and 76 are connected by a planetary gearing comprising a gear 77 fixed on the shaft 75, a gear 78 fixed on the shaft 76, and cluster gears 79 and 80 meshing respectively with the gears 77 and 78 and fixed on a shaft 81 journaled in the wall 73 and end plate 72.

5 A speed-control clutch mechanism is mounted within the housing 66 and is adapted in one position of adjustment to connect the shaft 75 for rotation with the pulley 64 to establish a rapid transverse drive, and in the other position of adjustment to lock the shaft 75 and the gear 77 against rotation to establish a feed drive. In the present instance, the clutch mechanism comprises a friction clutch 83 which is operable when engaged to connect the shafts 71 and 75 for rotation as a unit, and a friction clutch 84 which is operable when engaged to hold the shaft 75 against rotation.

10 Slidable on the shaft 75 for movement in opposite directions alternately to engage the rapid traverse and feed clutches 83 and 84 is a sleeve 85 having a peripheral groove 86. A clutch yoke 87 is fixed on a transverse rock shaft 88 journaled in the clutch housing 66, and has two shoes 89 engaging in the groove 86. A crank arm 90 is fixed on the outer end of the shaft 88, and engages in a notch in one end of a piston rod 91. A hydraulic actuator 92 on one side of the housing 66 comprises a cylinder 93 and a piston 94 reciprocable therein and connected to the rod 91. Suitable fluid supply lines 95 and 96 open to opposite ends of the cylinder 93. It will be seen that upon upward movement of the piston 94, the clutch 83 will be engaged to establish the rapid 15 traverse drive for the spindle 8 at any one of ten different rates depending upon the speed of the motor 56 and the selective engagement of the belt 63 with the pulley grooves 65. Upon downward movement of the piston 94, the clutch 83 will be disengaged, and the clutch 84 will be engaged to lock the shaft 75 against rotation. Thereupon, the gear 79 will roll about the gear 77 and cause the gear 80 to transmit a slow feed drive through the gear 78 to the shaft 76.

20 The shaft 58 of the reduction gearing 59 is journaled at opposite ends in bearings 97 and 98. The bearing 97 is mounted in a lug 99 within the base slide 20, and the bearing 98 is mounted within a tubular cup 100 secured in a bore 101 in the front wall of the slide. A worm 102 is fixed on the shaft 58, and meshes with a worm wheel 103 secured for rotation with the drive shaft 60. In the present instance, the worm wheel 103 is a ring gear bolted to a peripheral flange 104 on a sleeve 105 slidably splined for relative axial movement to the shaft 60. Opposite ends of the sleeve 105 are rotatably supported in suitable bushings 106 in two spaced bearing blocks 107. More particularly, each of the bearing blocks 107 is formed with oppositely extending lugs 108 resting on and bolted to a mounting web 109 within the base slide 20. The bearing blocks 107 confine the sleeve 105 and the worm wheel 103 against axial movement within the base 25 slide 20, while the shaft 60 is adapted for independent axial movement.

The slide plate 42 on the base slide 20 is formed with a longitudinal slot 110. Projecting downwardly through the slot 110 from the underside of the work slide 37 is a lug 111 formed with a cylindrical opening 112 in one side. A cylindrical bearing cup 113 is removably secured within the opening 112 and against one side of the lug 111 and serves to confine a bracket plate 114 in position against the lug. The forward end of the drive shaft 60 is rotatably supported in antifriction bearings 115 within the housing 113, and is anchored therein for axial movement with the work slide 37.

30 The gear-change mechanism 61 for connecting

the drive shaft 60 to the spindle 8 comprises a gear 116 fixed on the shaft, and meshing with one of two cluster gears 117 and 118 rotatably supported on the plate 114. The other of the cluster gears 117 and 118 meshes with one of two cluster gears 119 and 120 also supported for rotation on the plate 114. Slidably splined to the spindle 8 for rotation therewith and for axial adjustment thereon is a shiftable gear element 121 having two spaced gears 122 and 123. In the intermediate position, the gear element 121 is disengaged from the cluster gears to interrupt the drive to the spindle 8. In one end position of the gear element 121, the gear 122 will engage the gear 117 to establish a rotary spindle drive in one direction. In the opposite end position of the gear element 121, the gear 123 will engage the cluster gear 120 to establish a rotary spindle drive in the opposite direction.

To provide means for selectively adjusting the direction of the spindle drive, the gear element 121 is formed between the gears 122 and 123 with a peripheral groove 124 engaged by an eccentric pin 125 on a shaft 126 journaled in and extending through the front of the spindle housing 38. A lever 127 fixed on the outer end of the shaft 126 is movable over an arcuate sector 128 on the front of the housing 38, and has a detent 129 adapted for selective engagement with suitable apertures 130 in the sector to locate the gear element 121 in its different positions of adjustment.

It will be seen that the gear-change mechanism 61 permits convenient reversal of the drive connection to the spindle 8 to accommodate either threads having a right-hand lead or threads having a left-hand lead. When the gear element 121 is adjusted into its intermediate position, the spindle drive is disconnected and the spindle can be rotated manually by grasping the end plate 47 to index the latter as required, for multiple thread workpieces W. Suitable graduations 131 on the end plate 47 permit correct indexing for any number of work threads.

A drive is taken from the shaft 60 for translating the work slide 37 axially of the spindle 8 in timed relation to the spindle rotation. In the present instance, the translatory drive comprises a tubular master lead screw 135 removably keyed on a reduced outer extension 136 of the shaft 60 and clamped axially in position thereon by means of a cap screw 137. The master lead screw 135 is formed with a thread having the same pitch as the thread of the workpiece W to be ground, and is correlated to the hand of the work thread. If a work thread of opposite hand is to be ground, the change-gear mechanism 61 is adjusted to reverse the rotation of the spindle 8 in relation to the rotation of the shaft 60.

The lead screw 135 is in threaded engagement with a split nut 138 which is anchored against rotation and adjustably held in a fixed axial position. In the present instance, the nut 138 is removably bolted to a U-shaped carrier 139 having laterally extending lugs 140 on opposite sides, slidably resting on spaced parallel ways 141 in the base slide 20. The inner end of the bracket 139 is formed integral with a plate 142 having an axial opening 143. An annular bearing plate 144 is bolted to the plate 142, and an anchor sleeve 145 extends rotatably through the plate 144 into the opening 143. The outer end of the sleeve 145 is formed with a peripheral end flange 146, and suitable roller bearings 147 are disposed in end thrust engagement between the flange and

one side of the plate 144. A thrust washer 148 encircles the sleeve 145, and suitable roller bearings 149 are interposed in end thrust engagement between the washer and the other side of the plate 144. The washer 148 is confined in position and seats for universal alinement against an annular nut 150 threaded onto the sleeve 145. Consequently, the carrier 139 and the sleeve 145 are connected for independent relative rotation and against relative endwise movement.

The inner end of the sleeve is externally screw threaded, and in engagement with a split nut 151 having side lugs 152 bolted in fixed position to two supporting flanges 153 within the base slide 20. Normally, the nut 151 serves to anchor the sleeve 145 and the carrier 139 as a unit in a fixed axial position. A lead pick-up mechanism is provided for rotating the sleeve 145 to shift the nut 138 axially as required to locate the work thread in accurate relation to the grinding wheel G. In the present instance, the lead pick-up mechanism comprises an annular spiral gear 154 which is bolted to a flanged collar 155 confined on the sleeve 145 against the nut 150 by a clamp nut 156. The spiral gear 154 meshes with a worm 157 keyed in a fixed axial position to a cross shaft 158. The forward end of the shaft 158 extends into the rear end of a tubular adjusting shaft 159, and is splined thereto for joint rotation and relative axial movement. The shaft 159 extends through a tubular bearing bracket 160 removably mounted in a bore 161 in the front wall of the base slide 20, and is journaled therein at opposite ends in suitable bearings 162 and 163. A suitable hand dial or wheel 164 is rigidly connected to the forward end of the shaft 159 over a stationary disk 165 on the outer end of the bearing bracket 160. The disk 165 is formed on the front face with concentric annular flanges 166 and 167. Two aligned clamping pins 168 are radially disposed between the flanges 166 and 167, and at their adjacent ends are in wedge engagement with a ball 169. A clamp screw 170 is threaded through the hand wheel 164, into engagement with the ball 169, and when tightened will cause the ball to spread the pins 168 endwise into clamping engagement with the flanges 166 and 167 to lock the shaft 159 against rotation. When the screw 170 is released, the hand wheel 164 can be rotated to pick up the work thread.

A backlash compensating device is associated with the lead pick-up mechanism for independently adjusting the position of the master lead nut 138 in one direction or the other upon reversal of rotation of the lead screw 135. In the present instance, the backlash compensating device comprises a hydraulic actuator 171 for shifting the worm 157 axially through a predetermined adjustable distance to rotate the spiral gear 154 the amount required to compensate for backlash. The actuator comprises a cylinder 172 mounted in a bore 173 in the rear wall of the base slide 20, and enclosing a piston 174 connected to the rear end of the worm shaft 158. The cylinder 172 has fluid supply lines 175 and 176 opening to opposite ends thereof.

Mounted in the outer end of the cylinder 172 is an antifriction bearing having an inner raceway 177 adapted for engagement by a washer 178 on the inner end of the shaft 158 to constitute a rotary stop abutment defining the rearward limit of movement of the worm 157. The forward limit of movement is defined by an abutment consisting of a rod 179 adjustably disposed within the tubular shaft 159 for end engagement

by the forward end of the worm shaft 158. The rod 178 is axially adjustable within the shaft 158 but is confined against relative rotation by a key 180. An adjusting shaft 181 is rotatably confined by a plate 182 on the wheel 164 within a counterbore 183 in the forward end of the shaft 158 and has a rearward axial adjusting screw 184 in threaded engagement with the forward end of the abutment rod 178. Suitable wedge pins 185 are slidably disposed in cross bores within the shaft 181, and are adapted to be actuated by a clamp screw 186 into engagement with the surface of the counterbore 183 to lock the screw 184 against rotation within the shaft 158. When the screw 186 is released, the shaft 181 may be manually rotated to adjust the range of movement of the worm 157 as required to compensate for the backlash. A micrometer dial 187 is fixed on the outer end of the shaft 181, and serves to indicate the amount of backlash compensation.

The various fluid supply and return lines 85, 86, 175 and 176, as well as a drain line 190, for the clutch actuator 82 and the backlash actuator 171, are connected through a manifold to the hydraulic system. The manifold comprises a movable block 184 bolted to one end of the base slide 20, and formed with cored fluid passages connected respectively to the actuator lines. A plurality of parallel pipes 192, which extend longitudinally of the ways 2, are anchored at their outer ends to the block 184 in communication respectively with the passages therein. The other or inner ends of the pipes 192 extend slidably into individual bores 193 formed in a stationary block 194 rigidly mounted on the machine base 1 between the ways 2. In each instance, each pipe 192 opens at its inner end to the associated bore 193 and extends slidably through a fluid-tight packing 195 in the outer end of the bore. The packing 195 is maintained under compression by a spring 196, and is formed with a labyrinth groove 197 for intercepting and returning any leakage to drain. A plurality of passages 198 are formed in the manifold block 184 and in the base of the machine for connection with suitable conduits constituting, in effect, continuations of the lines 85, 86, 175, 176 and 190. The two blocks 184 and 194, together with the pipes 192, therefore, constitute a slip connection of the trombone type interposed in the fluid lines for the hydraulic actuators on the tool head 3 and permit adjustment of the base slide 20 without requiring the use of flexible conduits.

The work slide 31 has an idle position in which the spindle 8 is axially retracted from the tool head 3 to permit loading and unloading of the work. In the normal operating cycle of the machine, as will hereinafter be more fully described, the work slide 31 is translated toward and from the grinding wheel G in rapid approach and return movements, and is adapted to be translated in the working range at a rapid traverse or feed rate in either direction in accordance with the particular program of movements selected for grinding the workpiece.

A plurality of control switches LS₁, LS₂ and LS₃ are mounted on the front of the base slide 20 for engagement by adjustable control dogs on the side of the work slide 31 to control the program of rapid traverse and feed movements. The switch LS₁ determines the length of the rapid approach and rapid return movements, and is adapted for engagement by two control dogs 203 and 204 mounted on the work slide 31 for independent adjustment along a longitudinal guide slot 202.

The dog 203 is operative to lift the actuator of the switch LS₁ at the end of the rapid approach movement, and the dog 204 is operative to depress the switch actuator at the end of the rapid return movement into idle position. The switch LS₂ controls the length of the working range of the work slide 31, and is adapted to be actuated by two spaced dogs 203 and 204 mounted for adjustment along the guide slot 202. At the end of the forward pass, which may be either in feed or rapid traverse, the dog 203 will lift the actuator of the switch LS₂ to institute reversal of the work head motor 56. At the end of the return pass, which also may be either in rapid traverse or feed, the dog 204 will depress the actuator for the switch LS₂ either to terminate the working reciprocation and institute rapid return of the work slide 31 into idle position, or to reverse the slide for another cycle of passes across the grinding wheel G.

The switch LS₃ is an interlock to prevent shifting of the tool head 6 out of either end position unless the work head 3 is in the withdrawn idle position. Thus, the switch LS₃ is arranged to be actuated by the dog 203 at the end of the rapid return movement of the work slide 31, and when actuated permits the tool head 6 to retreat from the operative position into the idle or dressing position.

The tool head

The tool head 6 is mounted on a pedestal 205 formed on the top of the base extension 2, and comprises a wheel slide 206 shiftable transversely of the work spindle 8. To guide the slide 206, a rectangular plate 207 is mounted on the top of the pedestal 205, and is formed along opposite sides with longitudinal V-ways 208. The top wall of the pedestal 205 and the guide plate 207 are each formed intermediate the ways 208 with a longitudinal slot or opening 209. The wheel slide 206 has depending side flanges 210 supporting V-ways 211 disposed in opposed relation to the ways 208. Suitable roller bearings 212 are interposed between the complementary surfaces of the ways 208 and 211 to complete the guide relationship.

The grinding wheel G is mounted on the front of the wheel slide 206 for vertical and angular adjustment. To support the grinding wheel G, the slide 206 is formed on the forward end portion with an upstanding vertical bracket 213 having a front mounting face 214. A hollow rectangular base block 215 is secured to the bracket 213 in position against the face 214, and is formed in the front with spaced arcuate T-slots 216 concentric about the center of the grinding wheel G. A spindle bracket 217 is mounted against the front of the base block 215, and is adapted to be adjusted angularly along the slots 216 by an adjusting device having an actuating screw 218 to incline the grinding wheel in accordance with the lead of the work thread. The specific adjusting means is disclosed in a copending application, Serial No. 363,445, filed October 30, 1940, by Ira J. Snader, now Patent No. 2,316,816, issued April 20, 1943.

The spindle bracket 217 is formed at its lower end with a split tubular sleeve or housing 219 in which a bearing unit 220 supporting the spindle 7 is adjustably clamped. One end of the spindle 7 supports the grinding wheel G, and the other end projects from the bearing unit 220 for connection to a suitable drive in all positions of angular adjustment of the bracket 217. It will be understood that the spindle bearing unit 220 is axially

adjustable within the sleeve 219 to adapt the tool head 6 for workpieces W of different lengths.

The wheel drive comprises a pulley 221 secured to the rear projecting end of the spindle 7, and connected through a flat belt 222 to a pulley 223 on a parallel shaft 224 journaled in the upper end of the spindle bracket 217. An idler pulley 225 engages one flight of the belt 222 to tension the latter, and is mounted on a stub shaft 226 also journaled in the bracket 217. Another pulley 227, fixed on the shaft 224, is connected through a belt 228 to the pulley 229 of an electric drive motor 230 mounted on the rear end portion of the wheel slide 206. The motor 230 is supported on a cradle 231 for angular adjustment in accordance with the adjustment of the spindle bracket 217 so as to maintain the pulleys 227 and 229 in line. Suitable eccentrics 232 and 233 are provided in the spindle bracket 217 for adjusting the pulleys 225 and 227 to tension the belts 222 and 228.

The wheel slide 206 is adapted to be translated hydraulically either forwardly into an operative or grinding position, or rearwardly into an idle or dressing position. To this end, the slide 206 is formed with two spaced depending lugs 234 and 235 projecting through the slot 209 into the interior of the base extension 2. A piston rod 237 is connected at one end by a pin 238 to the lower end of the lug 234. The other end of the rod 237 is connected to an hydraulic actuator 238 which comprises a cylinder 239 mounted in a sleeve 240 in the rear end wall of the base extension 2, and a piston 241 reciprocable in the cylinder. Suitable fluid supply lines 242 and 243 open to the cylinder 239 at opposite sides of the piston 241.

The operative and idle positions of the wheel slide 206 are determined by an intermediate abutment member 247 carried by the lugs 234 and 235, and reciprocable between and respectively into opposite end engagement with spaced front and rear stops 248 and 244. The rear stop 244 is fixed, and consists of a cylindrical block secured in and extending through a bore 245 in the rear end wall of the pedestal 205. The front stop 248 forms part of the cross feed mechanism, 9, and is normally stationary, but adjustable for size control. The intermediate abutment 247 is in axial alignment with the stops 244 and 248, and consists of an adjusting screw 248 threaded through a nut 249 fixed in the lug 234, and a rear shaft extension projecting slidably through a bushing 250 fixed in the lug 235. It will be understood that the opposite ends of the member 247 constitute the abutment faces.

Suitable yieldable bumpers 251 are mounted in the opposite ends of the intermediate abutment member 247 to cushion the shock of engagement with the fixed stops 244 and 248.

In the present instance, the bumpers 251 are of the dash-pot type. Thus, the abutment member 247 is formed in opposite ends with two dash-pot cylinders 253 interconnected by an axial bore 254. Each bumper 251 is fixed to a piston 252, and normally projects slidably through a replaceable impact block closing the outer end of the cylinder 253. A stem 255 on the inner end of the piston 252 extends slidably into the adjacent end of the bore 254, and is formed with a restricted longitudinal passage 256 connecting the bore 254 to the inner end of the cylinder 253. The intermediate bore 254 opens through a radial port 257 to a wide annular groove 258 in the bushing 250. The groove 258 is in constant communication with the port 257 in all axial posi-

tions of the member 247, and opens upwardly through a passage 259 into the bottom of a liquid well 260 formed in the wheel slide 206. It will be evident that fluid from the well 260 will tend to flow through 259—258—257—254—256 into the bores 253 to urge the plunger 252 outwardly.

Upon engagement of either abutment member 247 with the associated end stop 244 or 246, the piston 252 will be forced inwardly, and the restricted escape of fluid from the cylinder 253 through the passage 256 will dampen or cushion the impact. When the abutment member 247 is moved from the stop, fluid from the well 260 will refill the cylinder 253 to move the bumper 251 outwardly into normal position.

Grinding wheel dressing

The dressing mechanism 11 for the grinding wheel G may be of any suitable type, and in the present instance is similar to that disclosed in copending application Serial No. 221,374, filed July 6, 1938, by Harold N. Seyferth and Ira J. Snader (now Patent No. 2,281,719, issued May 5, 1942). It comprises a sub-base 270 mounted in a fixed position on a pedestal 271 on the base extension 2, and is operable to dress the cutting surfaces of the grinding wheel G when the tool head 6 is in the idle position defined by the rear stop 244. The dressing mechanism includes two tools D arranged to traverse the grinding wheel G in a forward stroke and a return stroke during each dressing cycle. The actuating mechanism for the tools D is enclosed in a housing 272 mounted on a cradle 273 on the base 270 for angular adjustment about a transverse axis through the center of the wheel so as to conform to the adjustment of the spindle bracket 217 for the thread lead, and is adapted to be operated through a flexible shaft 274 by an electric motor 275 mounted on the rear of the base extension 2. Two limit switches LSDF and LSDR in the housing 272 are operable respectively to stop the forward and return dressing strokes of the tools D.

Prior to each dressing operation, an incremental dresser feed is imparted to the wheel slide 206 to shift the grinding wheel G further toward the dressing tools D. The dresser feed mechanism includes a gear 276 fixed on the movable abutment member 247 between the lugs 234 and 235, and operable in each impulse to rotate the adjusting screw 248 so as to retract the rear end axially an extent equal to the desired dresser feed increment. The dresser feed is instituted by actuation of a limit switch LS2 upon movement of the tool head 6 into idle position. More particularly, the switch LS2 is mounted on the rear of the pedestal 205, and has a rod 277 extending longitudinally through the block 244 for engagement by the abutment member 247. The forward adjustment of the abutment member 247 on the slide 206 causes the wheel G to shift rearwardly beyond its previous idle position to the extent of the feed movement.

The gear 276 meshes with an elongated pinion 278 in all positions of the wheel slide 206. The pinion 278 is rotatably supported at opposite ends in suitable bearing lugs 279 projecting inwardly from a cover plate 280 mounted on one side of the base extension 2. A spiral gear 281 rotatable with the elongated pinion 278 meshes with a spiral gear 282 on a transverse shaft 283. One end of the shaft 283 is rotatably supported in a bearing 284 on the inner face of the cover plate 280, and the other end extends through an intermediate bearing 285 into an integral housing 286 in the

opposite side wall of the base extension 2 and closed by a cover plate 287. The shaft 283 extends from the housing 286 through the cover plate 287 and a face plate 288 in an outer wall 289 on the base, and is provided at its outer end with a suitable hand wheel 290 available for manual operation.

The housing 286 encloses suitable drive means for automatically operating the dresser feed shaft 283. In the present instance, the drive means comprises a ratchet 291 keyed to the shaft 283, and a gravity pawl 292 adapted for engagement with the ratchet and mounted on the end of a pawl carrier or arm 293 oscillatory about the shaft. The free end of the pawl carrier 293 is pivotally connected through a link 294 to crank pin 295 adapted to be revolved by an hydraulic actuator 296 through one-half revolution in each feeding operation. The hydraulic actuator 296 comprises a cylinder 297 integral with a mounting bracket 298 secured to the inner wall of the housing 286, and a piston 299 reciprocable therein. Fluid supply lines 300 and 301, adapted to be alternately connected to a source of pressure fluid, open to the cylinder 297 at opposite end of the piston 299. The crank pin 295 is revolvable by a shaft 302 journaled in a boss 303 on the cylinder 297. A pinion 304, fixed on the shaft 302, meshes with a gear rack 305 formed in one side of the piston 299. Movement of the piston 299 first in one direction and then in the reverse direction through the full range will revolve the crank pin 295 back and forth through one-half revolution to oscillate the pawl 292 initially in a forward feeding stroke and then in a free return stroke.

Means is provided for adjusting the effective length of the pawl stroke, and preferably this means comprises an arcuate shield 306 mounted for angular adjustment about the shaft 283, and projecting beyond the periphery of the ratchet 291 for engagement by the pawl. The position of the shield 306 may be adjusted by means of a lever 307 fixed on the outer end of a rock shaft 308 journaled in and extending through the cover plate 287. A lever arm 309 is secured to the inner end of the shaft 308, and is notched at its free end for engagement with a pin 310 projecting laterally from the shield 306. The adjustment lever 307 is provided with suitable graduations for indicating the extent of the dresser feed, and may be secured in adjusted position by means of a clamp screw 311.

A single lobe cam 312 is secured for rotation with the shaft 302, and coacts with a limit switch LS5 in the housing 286 to initiate the dressing cycle at the completion of the dresser feed. Normally, the switch LS5 is open. The first full stroke of the piston 299 serves to move the pawl 292 through the forward feeding stroke and to revolve the high point of the cam 312 through one-half revolution to close the switch LS5. Subsequently, during the dressing cycle, the piston 299 is moved in the reverse direction to return the pawl 292 and to reopen the switch LS5.

Upon each dresser feed operation, the operative position of the grinding wheel G in relation to the workpiece W is automatically adjusted independently of the cross feed mechanism 9 to compensate for the reduction in diameter of the grinding wheel resulting from the removal of stock in the dressing operation. The dresser feed compensation occurs automatically upon adjusting the dresser feed screw 248 to accomplish the dresser feed. As the rear impact face of the movable abutment member 247 is adjusted forwardly

to permit increased movement of the tool head 6 rearwardly toward the dressing mechanism 11, the front impact face of the abutment member is adjusted forwardly relatively to the wheel slide 206 to the same extent. Consequently, the operative position of the tool head 6 is adjusted rearwardly to the extent of the dresser feed.

Wheel feed mechanism

The cross feed mechanism 9 for the grinding wheel G is operable to adjust the position of the forward stop 246, and thereby to control the size setting of the grinding wheel in relation to the workpiece W. The mechanism is manually operable to adjust the grinding wheel into initial setting as required by the diameter of the particular workpiece W to be ground, and during the machine cycle is automatically operable to impart a cross feed increment of predetermined depth once for each reversal of the work head 3 until the thread is ground to final size or depth. The stop 246 is also adjustable independently of the cross feed to retract the grinding wheel G from the workpiece W during rapid traverse operation, and to shift the grinding wheel progressively for taper grinding.

In its preferred form, the cross feed mechanism 9 comprises a body bracket 320 mounted in a recess 321 in the front of the base 1, and having a face plate 322 at the front end. The bracket 320 is formed in the front end portion with a chamber 323 closed at the top by a cover plate 324, and in the rear end portion with a tubular extension 325 having a bore 326 opening therethrough.

A sleeve 327 is rotatably disposed in the bore 326 and is confined against endwise movement by means of a key 328 mounted in the body bracket 320 and extending through a peripheral keyway or slot 329 in the sleeve. The forward end portion of the sleeve 327 is formed with an external gear 330. A piston 331 is reciprocable transversely of the sleeve 327 in a cylinder 332 in the body bracket 320, and is formed in one side intermediate its ends with a gear rack 333 in mesh with the gear 330. The piston 331 and cylinder 332 constitute an actuator 334 having inlet and discharge fluid lines 335 and 336 opening to opposite ends, and operable to effect rotation of the sleeve 327 alternately into two opposite limit positions. Normally, the sleeve 327 is held stationary in one position of rotation or the other.

Extending slidably through the sleeve 327 is a coaxial sleeve 337 having a tubular internal feed nut 338 on the forward end. The inner end of the key 328 extends through a wide longitudinal slot 339 in the sleeve 337 without restraining the latter against rotation and axial movement. A spline key 340 connects the sleeves 327 and 337 for joint rotation and relative axial movement.

The size control stop 246 is mounted in the rear end of the sleeve 337. In the preferred construction the stop 246 consists of a cylindrical body enlarged at the front end to define a radial shoulder 341. A screw fitting 342 is secured coaxially to the front end of the stop 246 by a draw bolt 343, and is threaded into a counterbore 344 in the rear end of the sleeve 337.

Extending through the sleeve 337 is a coaxial sleeve 345 which is formed at the forward end with an external screw 346 in engagement with the retract nut 338, and which is internally threaded to constitute a feed nut. The key 328 engages in a longitudinal spline groove 347 in the sleeve 345 to restrain the latter against rotation

while permitting axial movement. Extending into adjustable threaded engagement with the feed nut 345 is a cross feed screw 348 normally anchored in fixed axial position. Rotation of the screw 348, as in the cross feed, will shift the nut 345 and the sleeve 337 axially as a unit to adjust the stop 246. Rotation of the sleeve 327, as in the retract adjustment, will rotate the nut 338 on the screw 346 of the nut 345 to adjust the sleeve 337 and the stop 246 independently of the cross feed nut 345 and screw 348. If the screw 348 is shifted axially, as for taper grinding, the entire assembly will move therewith as a unit to adjust the stop 246.

The cross feed screw 348 has a forward shaft extension 349 normally anchored endwise by a follower bar mechanism 350 mounted on the body bracket 320 within the chamber 323. The mechanism is selectively adjustable to maintain the screw 348 in a fixed axial position for straight grinding, or to shift the screw bodily for taper grinding. More particularly, the screw 348 extends through and is supported in suitable ball bearings 351 in opposite ends of a guide block 352 mounted for axial sliding adjustment with the screw on a fixed guide 353 in the chamber 323. A roller 354 is mounted on the top of the block 352, and engages the rear longitudinal face of a control bar 355. One end of the bar 355 is rigidly connected through a rod 356 to a lug 357 on the work slide 31 for longitudinal movement therewith, so that the bar is longitudinally reciprocable with the work head 3. It will be understood that the bar 355 coacts with the roller 354 to limit the forward position of the cross feed screw 348. When grinding cylindrical work, the face of the bar is located parallel to the work spindle 8 so that the block 352 remains stationary. When grinding taper work, the face of the bar is located at an angle so that, as the workpiece W is reciprocated, the block 352 together with the cross feed screw 348 will be shifted axially in timed relation to reciprocation to generate the taper.

The forward end of the screw shaft extension 349 is splined for rotation and relative axial movement in a tubular shaft 358 journaled in a bushing 359 in the face plate 322 of the body bracket 320. A circular indexing plate 360, having an axial hub 361, is bolted concentrically to a peripheral flange 362 on the forward end of the stub shaft 358 so that the two are rotatable as a unit. An annular dog ring 363 formed in the periphery with a T-slot 364 is rotatable on the flange 362, and supports an annular internal ring gear 365. Meshing with the gear 365 is a planetary gear 366 mounted for rotation with a stub shaft 367 supported in and between the flange 362 and the index plate 360 to revolve therewith. A stub shaft 368 is confined in and extends through the hub 361 of the index plate 360, and coaxial sun gear 369 fixed to the inner end thereof meshes with the planetary gear 366. Fixed on the outer end of the stub shaft 368 is a hand wheel 370. A graduated ring 371 is rigidly secured to the index plate 360 and rotatably encircles the hand wheel 370. A second graduated ring 372 is rotatably disposed in a notch 373 in the periphery of the ring 371, and is secured against rotation by a key 374 bolted to a lug 375 on the front of the base 1. The hand wheel 370 is adapted to be adjustably connected to the index plate 360 for rotation therewith, or to be disengaged therefrom for independent rotation, by means of a retractable spring detent 376. The detent 376 is adapted for selec-

tive engagement in any one of a series of uniformly spaced index apertures 377 in the index plate 360.

When the detent 376 is engaged in one of the apertures 377, the cross feed drive is conditioned for power operation. In this condition of adjustment, the gears 365, 366 and 369 are locked to revolve as a unit, so that rotation of the dog ring 363 will be transmitted directly to the terminal shaft 358 to rotate the feed screw 348. When the spring detent 376 is disengaged from the index plate 360, the hand wheel 370 is manually rotatable independently of the dog ring 363 to adjust the feed screw 348 for the purpose of advancing the grinding wheel G into the initial size setting as determined by the diameter of the workpiece W. Rotation of the hand wheel 370 acts through the sun gear 369 to rotate the planetary gear 366 and cause the latter to roll along the stationary ring gear 365 thereby rotating the terminal shaft 358. The degree of adjustment is indicated by coarse graduations on the ring 371 against a reference point on the ring 372, and fine graduations on the ring 371 against reference points on the hand wheel 370.

A ratchet mechanism is provided for rotating the dog ring 363 through a predetermined degree upon each reversal of movement of the tool head 3. The ratchet mechanism comprises an annular ratchet wheel 378 having external teeth and rigidly secured to the dog ring 363 for rotation therewith. Rotatable on the outer end of the bushing 359 in position against the face plate 322 is a ring 379 formed with an arcuate gear sector 380, and with a radially extending arm 381 supporting a feed pawl 382 for engagement with the ratchet 378. The gear sector 380 meshes with a pinion 383 on the forward end of the shaft 384 journaled in and extending longitudinally through the front end of the body bracket 320. A pinion 385 on the inner end of the shaft 384 meshes with a rectilinear gear rack 386 slidable in a guide member 387 pivotally suspended from the shaft. The gear rack 386 is secured to the upper end of an adjustable connecting rod 388 which is pivotally attached at the other end to an eccentric pin 389 on a crank disk 390. Mounted on an inner base wall 391 within a chamber 392, normally closed by a removable cover plate 393, is a hydraulic actuator 394 for periodically rotating the crank disk 390 through one complete revolution. In the present instance, the actuator 394 comprises a cylinder 395 and piston 396 reciprocable therein. Suitable fluid supply lines 397 and 398 are connected to opposite ends of the cylinder 395. The piston 396 is formed intermediate its ends with a gear rack 399 which meshes with a pinion 400 on a shaft 401 journaled in the body of the cylinder 395 and supporting the crank disk 390. Upon each reversal of the piston 396, from one end of the cylinder to the other, the crank disk 390 is revolved through one complete revolution to oscillate the pawl 382 first in a forward feeding stroke, and then in a return stroke.

The depth of each feed increment is under the control of an adjustable shield 402 comprising an annular disk mounted for rotation on the bushing 359 between the pawl carrier ring 378 and the ratchet 378. The shield 402 has a peripheral sector 403 which projects beyond the periphery of the ratchet 378 in position to lift the pawl 382 from the teeth during an adjustable portion of the pawl stroke. A radial adjusting arm 404 extends through a notch 405 in a graduated ring 406

rotatably disposed in a groove 407 in the front of the face plate 322. In effect, the ring 406 and the arm 404 move as one. Suitable graduations on the ring 406 associated with a reference point on the face plate 322 indicate the degree of adjustment. After adjustment, the ring 406, together with the shield 402, is arranged to be secured in position by a clamp 408 engaged by the clamp screw 409.

A plurality of control dogs 410 and 411 are adjustably secured in the slot 364 of the dog ring 363, and are spaced in accordance with the depth of the thread to be ground. In the initial setting the hand wheel 370 is turned back manually to position the dog 411 against a stop shoulder 412 on the end of a size control lever 413 mounted on the front of the base 1. In the successive feeding operations, the dog ring 363 is rotated clockwise until the dog 410 engages a stop shoulder 414 on the lever 413 which determines the final depth of cut. Suitable graduations on the dog ring indicate the spacing of the dogs.

In the final feed increment, the stop dog 410 engages an inclined cam face 415 on the lever 413 to oscillate the latter out of operative position and thereby actuate a limit switch LS1 mounted within the chamber 392. One end of the lever 413 is secured to the outer end of a shaft 416 journaled in and extending eccentrically through a long bushing 417 rotatably supported in the front wall of the base 1. A depending lever 418 is fixed on the inner end of the shaft 416, and is formed with a notch 419 engaging the actuator of the switch LS1. When the lever 413 is actuated by the stop dog 410, the lever 418 is oscillated to open the switch LS1 and thereby initiate the end of the machine cycle. To start the next cycle, the starting dog 411 is moved counter-clockwise into the initial setting, and in this movement the dog 410 releases the hand lever 413. The latter is then returned into initial position against the peripheral face of the dog ring 363 to condition the machine for operation upon actuation of the starting control.

An arm 410 is fixed on the bushing 417 and is adjustable to rotate the bushing so as to retract the lever 413 out of the range of the dogs 410 and 411. A spring detent 421 on the arm 420 is selectively engageable in either of two recesses 422 to locate the lever 413 in retracted position or operative position. When the lever is in retracted position, the dog ring 363 is rotatable through any desired range to set the cross feed mechanism 9 for different work sizes. Movement of the wheel slide 206 into the operative position serves to close a limit switch LS1 at the rear of the base extension 4 to permit operation of the work head 3 and the cross feed mechanism 9. The switch LS1 is mounted on a bracket 423 guided by a pin 424 and fixed on the rear end of a tube 425. Both the pin 424 and the tube 425 are slidable in the rear wall of the base extension 4. Extending slidably through the tube 425 is a rod 426. The rear end of the rod 426 engages the actuating arm of the switch LS1, and the forward end is guided in the front of the base 1. A pin 427 extends diametrically through the tube 425 and a longitudinal slot 428 in the rod 426 to permit a limited relative axial movement sufficient to operate the switch LS1. A finger 429 is secured to the forward end of the tube 425, and adapted for engagement by the front side of the gear 276 carried by the slide

206. Fixed on the front end of the rod 426 is a collar 430 having a peripheral groove 431. A finger 432 secured to the stop 246 against the shoulder 341 engages in the groove 431. The finger 429 and the collar 430 are normally urged apart by a coiled compression spring 433 on the rod 426.

When the abutment member 248 nears the front stop 246, the gear engages the finger 429 to shift the tube 425 and the switch LS1 forwardly. The rod 426 is held against forward movement by the finger 432 and hence closes the switch LS1 as the wheel slide 206 moves into the forward operative position. In the return movement, the spring 433 causes the tube 425 to follow the gear 276 until the switch LS1 is again opened.

Hydraulic system

20 The various hydraulic actuators in the machine are connected in a hydraulic system, and are controlled automatically in predetermined timed relation by a plurality of solenoid operated direction valves.

25 Referring to Figs. 26 and 27, the hydraulic system includes a pump 434 adapted to be driven by an electric motor 435 and having an inlet line 436 taking fluid from a supply reservoir or sump 437 within the machine base 1. The pump 434 discharges fluid to a pressure line 438 which has a relief valve 439 opening back to the sump 437, and which is connected to the inlet ports of the respective control valves. Fluid discharging from the actuators is directed through the various control valves to a drain or exhaust line 440 returning to the sump 1.

30 In particular, the clutch actuator 92 is controlled by a two-position valve 441 normally biased into one end position by a spring 442 to connect the pressure line 438 to the cylinder line 96 and the cylinder line 95 to the drain line 440 so as to adjust the speed-change mechanism 57 normally for slow feed operation, and which is adapted to be actuated into the reverse position 35 by a solenoid SVS to reverse the line connections to establish the rapid traverse drive.

35 The hydraulic actuator 171 for the backlash compensating mechanism is controlled by a two-position valve 443 having a plunger connected at 50 opposite ends to two operating solenoids SVCR and SVCL. During the forward drive, the solenoid SVCR is energized to actuate the valve 443 into one end position in which the cylinder lines 176 and 175 are connected respectively to the 55 pressure and exhaust lines 438 and 440 to take up backlash in the proper direction. During the return drive, the solenoid SVCL is energized to actuate the valve 443 into the other end position, thereby reversing the connections to the cylinder lines 175 and 176 so as to take up the backlash in 60 the opposite direction.

60 The hydraulic actuator 238 for translating the grinding wheel slide 206 is controlled by a three-position valve 444 having a plunger 445 operatively connected at opposite ends to two actuating solenoids SVSO and SVSI. A spring 446 normally tends to bias the plunger 445 into neutral position to block the cylinder lines 242 and 243, for example while the tool head 6 is in the operative position or in the retreated position. Upon excitation of the solenoid SVSO, the valve plunger 445 is adjusted into the left-end position to connect the cylinder lines 243 and 242 respectively to the pressure and exhaust lines 438 and 75 440 so as to supply pressure fluid to the rear end

of the cylinder 239, and thereby advance the tool head 6 forwardly into the operative position. Upon energization of the solenoid SVSI, the connections to the cylinder lines 242 and 243 are reversed so that the actuator 238 is conditioned to translate the tool head 6 into the retreated position.

The hydraulic actuator 296 for the dresser feed is controlled by a two-position valve 447 having a plunger 448 connected to an actuating solenoid SVD. A spring 449 tends to bias the valve plunger 448 into one position in which the cylinder lines 301 and 300 are connected respectively to the pressure and exhaust lines 438 and 440 to locate the actuator 296 in normal idle position. Upon energization of the solenoid SVD, the valve plunger is shifted into the other end position to reverse the connections to the cylinder lines 300 and 301 to institute a dresser feed stroke. It will be evident that, in energizing and subsequently deenergizing the solenoid SVD, a forward feed stroke and a free return stroke will be imparted to the piston 299.

The hydraulic actuator 334 for retracting the grinding wheel G from the workpiece W during rapid approach and rapid return, and at all times when the grinding wheel is to take a free pass across the work, is controlled by a valve 450 having a plunger 451 connected at one end to an actuating solenoid SVRE. A spring 452 tends to bias the plunger 451 into one end position in which the cylinder lines 336 and 335 are connected respectively to the pressure and exhaust lines 438 and 440 to locate the wheel slide 206 in normal grinding position. Upon excitation of the solenoid SVRE, the valve 450 is reversed so as to effect reversal of the hydraulic actuator 334 to retract the grinding wheel G from the workpiece W.

The cross feed actuator 394 is controlled by a two-position valve 453 having a plunger 454 operatively connected at opposite ends to two actuating solenoids SVF1 and SVF2. In operation, normally one or the other of the solenoids is energized. When the solenoid SVF1 is energized, the cylinder lines 398 and 397 are connected respectively to the pressure and exhaust lines 438 and 440 so as to actuate the piston in one direction to impart an incremental cross feed to the wheel slide 206. When the solenoid SVF1 is deenergized and the solenoid SVF2 is energized, the valve 453 is reversed to reverse the connections to the cylinder lines, and thereby cause the piston 396 to move through its stroke into the other end position so as to impart another incremental cross feed to the wheel slide 206.

The various actuating solenoids for the valves are included in the electrical control system, wherein they are excited in predetermined timed sequence as required in the selected machine cycle.

Electrical control system and operation

Before proceeding with a description of the control circuits and operation, various elements are listed for convenient reference.

The electrical system includes the following electric drive motors:

Motor 53 for driving the coolant pump.

Motor 56 for driving and translating the work spindle 8.

Motor 230 for driving the grinding wheel G.

Motor 275 for actuating the dressing tools D.

Motor 438 for driving the hydraulic pump 434.

Motor 455 optionally available for a refrigerating unit.

The electrical system includes the following manual control switches, some of which are mounted in a panel 456 on the front of the machine base.

S1—For initiating operation of the hydraulic motor 435.

S2—Master stop switch.

S3—For starting the wheel motor 230 and the coolant pump motor 53.

S4—For stopping the wheel motor 230 and coolant pump motor 53.

S5—For starting the dresser motor 275.

S6—For selectively controlling dressing mechanism 11 to operate in an automatic cycle or to dress continuously under manual control, and to disable the dressing mechanism.

S7—For conditioning or disabling the automatic cross feed.

S8—For disabling the retract mechanism, or for selecting the direction of grind during which the wheel G is retracted.

S9—For selecting rapid or slow grind, and rapid or slow approach and return.

S10—For starting the automatic machine cycle.

S12—For stopping the automatic machine cycle.

S13—For conditioning the system to dress the grinding wheel G after a predetermined number of passes or the completion of one or more workpieces.

S15—For jogging the work head 3 to the left.

S16—For jogging the work head 3 to the right.

S51—For starting the dresser motor 275. (On rear of machine for dual control with switch S6.)

S61—For selectively controlling dressing mechanism 11 to operate in an automatic cycle or to dress continuously under manual control, and to disable the dressing mechanism. (On rear of machine for dual control with switch S6.)

The electrical system includes the following limit switches:

LS1—Closed when the slide 206 is in operative condition, to permit operation of the cross feed mechanism 9 and the work head motor 56.

LS2—Closed when the wheel slide 206 is in the idle position, to permit operation of the dresser feed.

LS2A—Closed when the wheel slide 206 is in operative position to permit completion of the grinding pass after final depth adjustment of cross feed.

LS3—Operated by the work slide 37 to determine the length of the work thread to be ground.

LS3A—Operated by the work slide 37 to condition the control for reversal at the end of the forward pass.

LS4A—Operated by the work slide 37 to determine the length of the approach movement.

LS4—Operable by the work slide 37 to prevent the wheel slide 206 from moving out of operative position when the work is out of idle position.

LS5—Operable at the completion of the dresser feed to initiate operation of the dresser motor 275.

LS6—Operable at the end of each cross feed increment to initiate operation of the work slide 37.

LS6A—Operable to energize the counter.

LS7—Operable upon cross feed to final depth, to initiate stopping of the machine cycle after completion of the grinding pass and return of the wheel slide 206 to idle position.

LS1A—Operable to effect return of the work

slide 31 to idle position after final size has been reached.

LS8—Engaged when the work slide 37 is in idle position to permit movement of the wheel slide 206 out of either end limit position.

LS9—Engaged when a hood 457 is over the work to permit actuation of the wheel slide 206 in either direction.

LSDF—For stopping the dressing cycle in the forward direction, and initiating operation in the reverse direction.

LSDR—For stopping the dressing cycle.

The electrical circuit includes the following valve operating solenoids:

SVRE—Operable when energized to effect retraction of the grinding wheel G from the workpiece during rapid traverse and for one-way grinding.

SDV—Operable when energized to institute the dressing feed.

SVS—Operable when energized to institute the rapid traverse drive for the work head 3.

SVSO—Operable when energized to institute movement of the wheel slide 206 to operative position.

SVSI—Operable when energized to institute movement of wheel slide 206 to idle position.

SVF1 and SVF2—Alternately operable to institute successive increments of cross feed for the wheel slide 206.

SVCR and SVCL—Operable alternately to reverse the backlash compensation.

The system also includes operating relays and switch contacts mounted on an electrical panel 458 on one end of the base 1.

Referring to the electrical circuits, current is supplied for all of the various motors from three main supply lines L₁, L₂, and L₃ which are adapted to be connected to a suitable source of three-phase alternating current. Suitable low voltage current for the control circuits proper is derived from a step-down transformer 459 having a primary winding connected across the lines L₁, and L₂, and a secondary winding connected at one terminal to a line L₄, and at the other terminal to a line L₅, in turn adapted to be connected to an auxiliary line L₆. The various control devices are adapted to be energized by connecting them respectively across either of the lines L₄ and L₅ or L₄ and L₆.

The motors 53, 230, 435 and 455 are adapted to be connected across the main lines L₁, L₂ and L₃ for continuous operation. Upon closing the switch S1, a circuit is completed for a relay H, which upon energization closes normally open contacts H¹ to establish a holding circuit across the switch S1, and closes switch contacts H² to close the circuits for the hydraulic motor 435.

Closing of the contacts H¹ connects the lines L₅ and L₆ and, therefore, conditions the entire system for operation. If the circuit for the relay H should be interrupted, the electrical system would be disabled.

Upon closing the switch S3, a circuit is completed for a relay C through the normally closed stop switch S4. Energization of the relay C closes normally open contacts C¹, C² and C³. The contacts C¹ establish a holding circuit for the relay C. The contacts C² condition the circuit for the relay FW which controls the forward operation of the work motor 56. The contacts C³ close the main circuits for the wheel motor 230 and the coolant motor 53. Also, a relay R is connected in parallel with the relay C, and, upon closing of a thermostat T, will be energized to close contacts

R¹ to institute operation of the refrigerator motor 455.

The electrical circuits are selectively adjustable to condition the machine for any one of a number of different automatic cycles. For illustrative purposes, the circuits will be described as conditioned for the automatic cycle represented in Fig. 23, and comprising advance of the wheel slide 206 into operative position (line a—b), a cross feed increment (b—c), rapid approach of the work slide 37 (c—d), movement of the slide 206 to the work form the retract position (d—e), a forward slow speed grinding pass of the work slide 37 (e—f), work reversal and a second cross feed increment (f—g), a return slow feed grinding pass (g—h), work reversal and a third cross feed increment (h—i), a second forward slow speed grinding pass (i—j), work reversal and a fourth cross feed increment (j—k) to final size, a second return slow feed grinding pass (k—l), rapid return of the work slide 37 into idle position (l—m), retreat of the wheel slide 206 into idle position (m—n), and automatic dressing of the grinding wheel G at the end of the cycle.

In the cycle of Fig. 24, the grinding wheel G is retracted during rapid approach and during the forward movements o of the work slide 37 which occur at a rapid traverse rate, and is in cutting position during the reverse movements to take a succession of five cutting passes p at a feed rate. Cross feed increments q are imparted at the start of approach and at each stroke reversal. Retract movements r are imparted to the wheel G at the end of each reverse cutting pass p except upon rapid return of the slide 37 to idle position. Counter-retract movements s are imparted to the wheel G at the end of each free forward stroke. The grinding is interrupted between the third and fourth cutting passes, as at t, to dress the wheel G.

The machine cycle of Fig. 25 is similar to that of Fig. 23, except that grinding occurs only during the forward work passes u. Retract movements r and counter-retract movements s occur respectively at the ends of the slow forward and fast reverse strokes.

To initiate the operating cycle of Fig. 24, the starting switch S11 is closed, thereby completing a circuit for relay CR1 through normally closed switches S12, S15 and S16. Switch S11 is held in closed position until relay CR1 opens contacts CR1¹ and CR1² and to close contacts CR1³ to CR1⁷. Contacts CR1⁶ close a circuit for the relay CR2 through limit switch LS7 and switch S12. Relay CR2 opens contacts CR2¹ and CR2² and closes contacts CR2³ to CR2⁹. Contacts CR1³ and CR2⁶, now being closed, establish a holding circuit across the starting switch S11. Also, contacts CR2⁷ establish a holding circuit for the relay CR2 across the contacts CR1⁵.

Contacts CR2³ and CR1⁴ close a circuit for the latch relay LR2 through limit switches LS8 and LS9, and energize the coil L which is latched in position. Energization of the relay LR2 opens contacts LR2¹ to deenergize the solenoid SVS0, and closes contacts LR2² to complete a circuit for the solenoid SVS1, thereby actuating the valve 444 to institute operation of the wheel slide 206 from the idle position forwardly into the operative position.

Upon movement of the wheel slide 206 out of idle position, the limit switch LS2 is opened and the limit switch LS2A is closed. The limit switch LS2 interrupts the circuit for the solenoid SVD, thereby preventing operation of the dresser feed

while the wheel slide is out of idle position. The switch LS2A closes a holding circuit across the contact CR2⁵ to maintain relays CR1 and CR2 energized when the limit switch LS1 is finally opened until the work slide 37 is returned to its idle position.

Upon movement of the slide 206 into operative position, the limit switch LS1 is closed to complete a circuit for the solenoid SVF1, thus instituting the first cross feed increment. During 10 the cross feed operation, the limit switch LS6 is open and prevents operation of the work head 3.

At the end of the cross feed operation, the switch LS6 is closed by the cam 390, and closes a circuit through the limit switch LS1 for the relay FW. Excitation of the relay FW opens contacts FW¹ to disable the circuit for relay REV, and closes contacts FW² and FW³. The contacts FW³ close the main circuits of the work motor 56 for operation in a forward direction.

Upon initiation of the motor rotation, a plugging switch P is adjusted into one station to complete a circuit for relay CR4 through the contacts FW². Excitation of relay CR4 opens contacts CR4¹, and closes contacts CR4² to CR4⁴. Contacts CR4³ serve to establish a holding circuit across the limit switch LS6 for the relay FW to permit operation of the cross feed mechanism without disabling the work drive. Contacts CR4⁴ establish a holding circuit across the contacts FW² to maintain the plugging circuit after deenergization of the forward relay FW.

To condition the work drive for rapid traverse operation during the approach and return movements, the switch S9 is adjusted into the rapid traverse station. At the start of the movement of the work slide 37, the limit switch LS4A is closed and the limit switch LS4 is open. Consequently, a circuit is completed for the solenoid SVS, which serves to connect the high speed drive.

At the end of the rapid approach, the work slide 37 closes the limit switch LS4 and opens the limit switch LS4A, thereby deenergizing the solenoid SVS to connect the feed drive, and completing a circuit for relay CR3. Excitation of the relay CR3 opens contacts CR3¹ to interrupt the circuit for the coil L of the latch relay LR2, and closes contacts CR3² to CR3⁴. The contacts of the relay LR2 remain latched to maintain the wheel slide 206 in operative position. Assuming that the switch S13 has been adjusted into its lowermost position for counting pieces, and that the counter has been set for a single workpiece, the contacts CR3³ close a circuit through the switch S13 for the actuator coil B of the counter. Excitation of the coil B closes switch B1 preparatory to subsequent completion of a circuit for coil CR6. Contacts CR3⁴, since contacts CR2⁹ and CR6⁸ are closed, establish a circuit for a solenoid V for opening a coolant valve (not shown) to supply coolant to the workpiece during the grinding reciprocation.

During the rapid approach and the forward feed, the limit switch LS3 is open and the limit switch LS3A is closed. The switch S8 controls the selective operation of the retract which is necessary only in a cycle where grinding occurs in one direction and not in the other. In the present cycle, the switch S8, therefore, is in open position. If the cycle included grinding only in the return direction, as in Fig. 24, the switch S8 would be adjusted into its "left" position and in this event would, with the switch LS3A, complete a circuit for the solenoid SVRE to shift the valve

5 450 into retracted position. If grinding in only the forward direction, as in Fig. 25, were desired, the switch S8 would be adjusted into the "right" position, thereby also closing the circuit for the solenoid SVRE. In each instance, reversal of the limit switches LS3 and LS3A at the end of the feed pass would break the circuit for the solenoid SVRE in the opposite direction of work movement.

Connected in parallel with the solenoid SVRE for excitation at the same time is relay CR8. Excitation of the relay CR8 serves to close contacts CR8¹ across the limit switch LS4A so as to maintain the solenoid SVS energized to continue 10 operation in rapid traverse during the entire forward stroke or the entire reverse stroke, depending on the setting of the switch S8.

Consequently, up to this point in the machine cycle, the tool slide 206 has been advanced into operative position and been given a cross feed, and the work slide 37 has been advanced, without retraction of the grinding wheel G in a rapid approach movement, and is in the forward feed movement.

At the end of the forward feed pass, the work slide 37 opens the limit switch LS3A and closes the limit switch LS3, thereby completing a circuit for coil L¹ of the latch relay LR1, and interrupting the circuit for the coil U¹. The relay LR1 is thereupon latched in position. Energization of the relay LR1 opens contacts LR1¹ to LR1³ and to close contacts LR1⁴ to LR1⁶. The contacts LR1¹ interrupt the circuit for the solenoid SVF1; the contacts LR1⁵ complete a circuit for the solenoid SVF2 to initiate a cross feed increment; and the contacts LR1² open the circuit for the relay FW to stop the forward operation of the work motor 56. Deenergization of the relay FW closes interlock contacts FW¹, and opens contacts FW², thereby completing a circuit for the relay REV through contacts CR4². At this time, the coil of the relay CR4 remains energized as long as the motor continues forward rotation to close the plugging switch P in the initial position. The motor 56 now decelerates rapidly to a stop, and starts to reverse. In the first increment of reversal, the plugging switch P is opened, thereby interrupting the circuit for the relay CR4 which opens contacts CR4², CR4³ and CR4⁴, and closes contacts CR4¹. Since the switch LS6 is open, the circuit for the relay REV is interrupted to finally stop the motor 56.

Reversal of the limit switches LS3 and LS3A at the end of the forward feeding stroke serves also to effect deenergization of the solenoid SVCR and energization of the solenoid SVCL, thereby causing operation of the hydraulic actuator 171 to reverse the backlash compensation for the return movement of the work slide 37.

During the cross feed operation, the cam 390 opens the limit switch LS6 to stop and prevent operation of the work motor 56. At the end of the cross feed operation, the switch LS6 is again closed to complete the circuit for the relay REV through the switches FW¹, CR4¹, CR3², LR1⁴, C2, LS6, CR1⁶, and LS1. Excitation of the relay REV opens contacts REV¹ to disable the circuit for the relay FW, and closes contacts REV². It also closes REV³ to start the motor 56 in the reverse direction of rotation. After commencement of the motor operation, the plugging switch P is closed in the reverse direction to complete a circuit for relay CR5, which upon excitation opens contacts CR5¹ and CR5² and closes contacts CR5³ to CR5⁶. The contacts CR5⁴ establish

a holding circuit across contacts REV² for the relay CR5. Contacts CR5⁶ complete a circuit across the limit switch LS6 to permit plugging at the next stopping of the work motor 56. Contacts CR5³ insure maintenance of the circuit for the relay CR2 if the switch S12 should be momentarily opened to stop the machine during a pass, to insure completion of the pass.

At the end of the return feed pass, the dog 204 opens switch LS8 and recloses switch LS3A, thereby interrupting the circuit for the coil L¹ and completing the circuit for the coil U¹ to unlatch the relay LR1. Consequently, relay contacts LR1⁴ to LR1⁶ are opened and contacts LR1¹ to LR1³ are closed. Contacts LR1⁴ interrupt the circuit for relay REV, and thereupon the work motor 56 will be stopped and conditioned for reverse operation in a forward direction in a manner similar to the stopping and reversal of the motor at the end of the forward feed pass. The backlash compensation is reversed, and a cross feed increment is imparted to the wheel slide 206.

The work slide 37 will continue to reciprocate back and forth in forward and return passes, with a wheel cross feed at the end of each feeding stroke, and a reversal of the backlash compensation upon each reversal of translation until the workpiece W is ground to the desired size, at which time limit switch LS7 is opened by the dog 410 on the feed wheel 370. If, when this occurs, the work slide 37 is conditioned for another feed pass in a forward direction, the contacts CR5¹ will be closed so that opening of the limit switch LS7 will not interrupt the circuit for the relay CR2. Consequently, the slide 37 will complete the forward pass, then stop, reverse, and move through another return pass and rapid return to the idle position. During the plugging at the end of this final forward pass, the contacts CR5⁵ are opened to deenergize relay CR2 which opens contacts CR2⁴ to prevent another cross feed increment at the final reversal of work translation. On the contrary, if the limit switch LS7 is opened by a final feed increment at the end of a forward pass, the slide 37 will merely reverse to complete one more return pass and then move into idle position.

At the end of the reverse feed pass, the work slide 37 opens limit switch LS3 and closes limit switch LS3A, but no cross feed will occur since the contacts CR2⁴ are open to interrupt the circuit for the solenoids SVF1 and SVF2. The motor 56 is not plugged to a stop and reversed at the end of the return feed pass, as it was at the end of intermediate passes to the left, for the reason that the limit switch LS7A is now closed, and maintains the circuit for relay REV independently of the contacts LR1⁴.

At the end of the rapid return, the work slide 37 closes the limit switch LS4A and opens the limit switch LS4, thereby deenergizing relay CR3 which opens contacts CR3¹ to open the circuit for the relay REV to initiate stopping of the motor 56. Contacts CR3¹ are also closed, which completes a circuit for coil U of the relay LR2 to unlatch coil L, thereby closing contacts LR2¹ and opening contacts LR2². As a result, the solenoid SVS6 is energized and the solenoid SVS1 is deenergized to effect return of the wheel slide 206 into its idle position.

Contacts CR3² are opened to deenergize relay B, thereby closing switch B¹ of the counter. At this time relay CR6 is energized so that contacts CR5⁵ are closed to complete a circuit through

relay CR6 which closes contacts CR6³ to establish a holding circuit across contacts CR5⁶ and switch B¹. Excitation of relay CR6 closes contacts CR6⁶.

5 When the wheel slide 206 reaches the fully retracted position, the limit switch LS2 is closed to complete a circuit for the solenoid SVD, which actuates the valve 447 to initiate the dresser feed cycle. At the start of the dresser feed, limit 10 switch LS5 is open. At the completion of the dresser feed, the cam 312 closes limit switch LS5, thereby completing a circuit for relay DF which opens contacts DF¹ in the circuit for the relay DR and closes contacts DF² to connect the circuit for the dresser motor 275, to initiate the dressing cycle. The dressing tools D are thereupon moved through their forward stroke across the cutting surfaces of the grinding wheel G. At the start of the forward dressing stroke, the 15 limit switch LSDR is closed. At the end of the forward dressing stroke, the limit switch LSDF is opened to deenergize relay DF, thereby closing contacts DF¹ to energize relay DR and opening contacts DF² to stop the forward rotation of the motor 275. Energization of the relay DR opens the contacts DR¹ and closes the contacts DR² to complete the circuits for the motor 275 for rotation in the reverse direction. Energization of relay DR also opens contacts DR³ to DR⁵, the contacts DR³ insuring inoperativeness of relay LR2, the contacts LR⁴ effecting deenergization of relay CR6, and the contacts DR⁵ effecting deenergization of the relay B. Deenergization of relay CR6 opens contacts CR6⁶ to deenergize solenoid SVD, thereby effecting idle return of the dresser feed mechanism into initial position. The limit switch LS5 is now opened. The dressing tools D move through their return stroke, at the end of which the limit switch 20 LSDR is opened to deenergize the relay DR, and thereby effect opening of contacts DF¹ and DF² to stop the dresser motor 275.

If the switch S13 had been adjusted into the "stroke" position, the contacts CR6⁴ would shunt 45 the switch LS7A so as to effect return movement of the work slide 37 into idle position, and dressing of the wheel G after the completion of the selected number of passes. However, the 50 cycle of the machine would not end since the limit switch LS7 would still be closed. Consequently, at the conclusion of the dressing operation, the machine cycle would be resumed to complete the grinding operation.

If the counter had been set for a plurality 55 of workpieces instead of a single piece, dressing would not occur at the end of any machine cycle until the selected number of pieces had been ground, i. e., until the limit switch LS7 had been opened a corresponding number of times.

If the switch S13 had been adjusted into the "off" position, the automatic dressing cycle would be disabled, and dressing would be subject only to manual control. When switches S6 and 65 S61 are in the "on" position shown, dressing will be intermittent, as described. Upon holding either of these switches in the "continuous" position, relay CR6 will be energized, when the contacts DR⁴ are closed at the end of each dressing cycle, so that the dressing cycle will repeat until the switch is released.

The machine cycle may be interrupted at any time to effect a cycle of dressing by closing one or the other of switches S5 and S51 which, when 75 closed, will shunt the automatic control switches

in the circuit for the relay CR6. In the "off" position, the switches S6 and S61 disable the dressing mechanism.

I claim as my invention:

1. A grinding machine comprising, in combination, a base, a work head supporting a spindle on said base for rotation and for axial translation out of idle position in forward and reverse directions of translation, a tool head supporting a rotary grinding wheel on said base for movement transversely of said spindle either in one direction into an operative position or in the other direction into a remote idle position offset with relation to said work head, and automatic interlock control means for preventing movement of said work head out of idle position unless said tool head is in operative position and movement of said tool head out of either of its positions unless said work head is in idle position.

2. A grinding machine comprising, in combination, a base, a work head supporting a spindle on said base for rotation and for axial translation out of idle position in forward and reverse directions of translation, a tool head supporting a rotary grinding wheel on said base for movement transversely of said spindle either in one direction into an operative position or in the other direction into a remote idle position offset with relation to said work head, drive means operative to reciprocate said spindle when said tool head is in operative position, a dressing mechanism mounted on said base and adapted to dress said wheel when said tool head is in idle position, and control means automatically operable after a predetermined number of work passes to interrupt said reciprocation and to return said tool head into idle position, and control means automatically operable to initiate operation of said dressing mechanism upon such return movement of said tool head into idle position.

3. A grinding machine comprising, in combination, a base, a work head supporting a spindle on said base for rotation and for axial translation out of idle position in forward and reverse directions of translation, a tool head supporting a rotary grinding wheel on said base for movement transversely of said spindle either in one direction into an operative position or in the other direction into a remote idle position offset with relation to said work head, drive means rendered operative to reciprocate said spindle upon movement of said tool head into operative position, a dressing mechanism mounted on said base and adapted to dress said wheel when said tool head is in idle position, means for imparting an incremental cross feed to said tool head for each cutting movement of said work head, and automatic control means operable after a predetermined extent of cross feed to interrupt said work reciprocation and return said tool head to idle position and then initiate operation of said dressing mechanism.

4. A grinding machine comprising, in combination, a base, a work head supporting a spindle on said base for rotation and for axial translation out of idle position in forward and reverse directions of translation, a tool head supporting a rotary grinding wheel on said base for movement transversely of said spindle either in one direction into an operative position or in the other direction into an idle position offset with relation to said work head, drive means operative to reciprocate said spindle when said tool head

is in operative position, a dressing mechanism mounted on said base and adapted to dress said wheel when said tool head is in idle position, means for imparting an incremental cross feed to said tool head for each cutting movement of said work head, automatic control means operable after a predetermined extent of cross feed to interrupt said work reciprocation and return said tool head to idle position, and automatic control means operable upon return of said tool head into said idle position to impart an incremental dresser feed to said tool head and at the end of said dresser feed to initiate operation of said dressing mechanism.

5. A grinding machine comprising, in combination, a base, a work head supporting a spindle on said base for rotation and for axial translation out of idle position in forward and reverse directions of translation, a tool head supporting a rotary grinding wheel on said base for movement transversely of said spindle either in one direction into an operative position or in the other direction into a remote idle position offset with relation to said work head, drive means operative to reciprocate said spindle when said tool head is in operative position, a dressing mechanism mounted on said base and adapted to dress said wheel when said tool head is in idle position, and automatic control means operable at a predetermined point in the grinding of a workpiece to temporarily interrupt said work reciprocation and temporarily return said tool head to idle position, and initiating operation of said dressing mechanism, and then effecting resumption of the grinding operation to final depth.

6. A grinding machine comprising, in combination, a base, a work head on said base and supporting a work spindle for rotation and axial reciprocation out of idle position in forward and return strokes, a tool head having a slide supporting a grinding wheel and movable on said base transversely of said work spindle, an intermediate abutment member carried by said wheel slide, a stationary rear stop adapted for engagement with one end of said abutment member to locate said wheel slide in idle position at one limit of its translation, a front stop adapted for engagement with the other end of said abutment member to locate said wheel slide in operative position at the other limit of its translation, a dressing mechanism mounted in fixed position on said base for operative engagement with said grinding wheel when said wheel slide is in said idle position, and means for automatically adjusting said abutment member longitudinally of said slide, whereby to impart a dresser feed to said grinding wheel when in said idle position, thereby effecting a compensatory cutting feed to said grinding wheel when in operative position.

7. A grinding machine comprising, in combination, a base, a work head on said base supporting a work spindle for rotation and axial reciprocation out of idle position in forward and return strokes, a tool head having a slide supporting a grinding wheel and being movable on said base transversely of said work spindle, an intermediate abutment member mounted for longitudinal adjustment on said wheel slide, a rear stop adapted for engagement with one end of said abutment member to locate said wheel slide in idle position at one end of its translation, a front stop aligned with said rear stop and adapted for engagement with the other end of said abutment member to locate said wheel slide in operative position at the other limit of translation, a dress-

ing mechanism mounted in fixed position on said base for operative engagement with said grinding wheel when in said idle position, and means for automatically adjusting said abutment member in a dresser feed longitudinally of said slide when said slide is in idle position and then initiating operation of said dressing mechanism.

8. A grinding machine comprising, in combination, a base, a work head on said base supporting a work spindle for rotation and axial reciprocation out of idle position in forward and return strokes, a tool head having a slide supporting a grinding wheel and being movable on said base transversely of said work spindle, an abutment member carried by said wheel slide and anchored thereto by a nut and screw connection, a stationary rear stop adapted for engagement with one end of said abutment member to locate said wheel slide in idle position at one end of its translation, a front stop adapted for engagement with the other end of said abutment member to locate said wheel slide in operative position at the other limit of translation, a dressing mechanism mounted in fixed position on said base for operative engagement with said grinding wheel when in said idle position, and means for automatically rotating said abutment member to adjust said member longitudinally of said slide.

9. A grinding machine comprising, in combination, a base, a work head on said base supporting a work spindle for rotation and axial reciprocation out of idle position in forward and return strokes, a tool head having a slide supporting a grinding wheel and being movable on said base transversely of said work spindle, an abutment member carried by said wheel slide and anchored thereto by a nut and screw connection, a stationary rear stop adapted for engagement with one end of said abutment member to locate said wheel slide in idle position at one end of its translation, a front stop adapted for engagement with the other end of said abutment member to locate said wheel slide in operative position at the other limit of translation, a dressing mechanism mounted in fixed position on said base for operative engagement with said grinding wheel when in said idle position, means for automatically rotating said abutment member to adjust said member longitudinally of said slide, and means automatically operable in timed relation to the work reciprocation to shift the position of said front stop longitudinally of said abutment member whereby to modify the operative position of said wheel slide.

10. A grinding machine comprising, in combination, a base, a work head on said base supporting a work spindle for rotation and axial reciprocation out of idle position in forward and return strokes, a tool head having a slide supporting a grinding wheel and being movable on said base transversely of said work spindle, an abutment member carried by said wheel slide and anchored thereto by a nut and screw connection, a stationary rear stop adapted for engagement with one end of said abutment member to locate said wheel slide in idle position at one end of its translation, a front stop adapted for engagement with the other end of said abutment member to locate said wheel slide in operative position at the other limit of translation, a dressing mechanism mounted in fixed position on said base for operative engagement with said grinding wheel when in said idle position, means for automatically rotating said abutment member to adjust said member longitudinally of said slide, and a cross-feed mechanism automatically operable in timed rela-

tion to the work reciprocation to shift said front stop step-by-step in a cross feed toward said fixed stop.

11. A grinding machine comprising, in combination, a base, a work head on said base supporting a work spindle for rotation and axial reciprocation out of idle position in forward and return strokes, a tool head having a slide supporting a grinding wheel and being movable on said base transversely of said work spindle, an abutment member carried by said wheel slide and anchored thereto by a nut and screw connection, a stationary rear stop adapted for engagement with one end of said abutment member to locate said wheel slide in idle position at one end of its translation, a front stop adapted for engagement with the other end of said abutment member to locate said wheel slide in operative position at the other limit of translation, a dressing mechanism mounted in fixed position on said base for operative engagement with said grinding wheel when in said idle position, means for automatically rotating said abutment member to adjust said member longitudinally of said slide, a cross-feed mechanism automatically operable in timed relation to the work reciprocation to shift said front stop step-by-step in a cross feed toward said fixed stop, and retract means automatically operable in timed relation to the work reciprocation to shift said front stop longitudinally of said abutment member and independently of said cross feed alternately in a retract movement and a counter-retract movement.

12. A grinding machine comprising, in combination, a base, a work head on said base supporting a work spindle for rotation and axial reciprocation out of idle position in forward and return strokes, a tool head having a slide supporting a grinding wheel and being movable on said base transversely of said work spindle, an abutment member carried by said wheel slide and anchored thereto by a nut and screw connection, a stationary rear stop adapted for engagement with one end of said abutment member to locate said wheel slide in idle position at one end of its translation, a front stop adapted for engagement with the other end of said abutment member to locate said wheel slide in operative position at the other limit of translation, a dressing mechanism mounted in fixed position on said base for operative engagement with said grinding wheel when in said idle position, means for automatically rotating said abutment member to adjust said member longitudinally of said slide, a cross-feed mechanism automatically operable in timed relation to the work reciprocation to shift said front stop step-by-step in a cross feed toward said fixed stop, and means automatically operable in timed relation to the work reciprocation to shift said front stop longitudinally of said abutment member and independently of said cross feed.

13. A grinding machine comprising, in combination, a base, a work head supporting a spindle and mounted on said base to rotate said spindle and to translate said spindle in timed relation to said rotation and in forward and reverse directions, a tool head supporting a rotary grinding wheel and mounted on said base for movement transversely of said spindle either into an operative position in line with said work head or into an idle position offset from said work head, cross feed means operable in timed relation to the translation of said work spindle to impart an incremental cross feed movement to said tool head, means for adjusting said cross feed means re-

versibly through a fixed range to retract or advance said tool head from or into cutting position when located in said operative position, and control means selectively adjustable to disable said last mentioned means or to effect retraction of said tool head for one direction or the other direction of the work reciprocation.

14. A grinding machine comprising, in combination, a base, a work head supporting a spindle and mounted on said base to rotate said spindle and to translate said spindle in timed relation to said rotation and in forward and reverse directions, a tool head supporting a rotary grinding wheel and mounted on said base for movement

5 transversely of said spindle either into an operative position in line with said work head or into an idle position offset from said work head, means for moving said tool head selectively into operative position or idle position, cross feed means operable when said tool is in operative position in timed relation to the translation of said work spindle to impart an incremental cross feed movement to said tool head, and means for adjusting said cross feed mechanism reversibly to retract or advance said tool head from or into cutting position when located in the operative position.

GUENTHER BRINKMANN.
